R. S. A. Lacey

UNITED STATES PATENT OFFICE.

CHARLES SPRINGER, OF TIDIOUTE, PENNSYLVANIA.

WAGON-JACK.

SPECIFICATION forming part of Letters Patent No. 339,590, dated April 6, 1886.

Application filed November 25, 1885. Serial No. 183,945. (No model.)

To all whom it may concern:

Be it known that I, CHARLES SPRINGER, a citizen of the United States, residing at Tidioute, in the county of Warren and State of

5 Pennsylvania, have invented certain new and useful Improvements in Wagon-Jacks; and I do declare the following to be a full, clear, and exact description of the invention, such as will enable others skilled in the art to which it 10 appertains to make and use the same, reference being had to the accompanying drawing, and to the letters and figures of reference marked thereon, which form a part of this specification.

15 My invention is an improved jack for use in oiling carriage and wagon axles; and it consists in certain novel features hereinafter fully described and claimed.

20 In the drawing I have shown a perspective view of my device, a portion of the hollow support being broken away.

25 In carrying out my invention I provide a base, A, upon which I erect a hollow internally-screw-threaded support, B, as shown. The standard C of the jack is provided with a 30 depending screw-threaded shank, D, which enters the support B and is held thereby. The upper portion, E, of the standard is provided with a slot, F, and a series of pivot-holes, G, on each side of the said slot. The lever H is passed through the slot F and pivoted upon a pin or bolt passed through the pivot-holes G, as will be understood. The short arm of this lever is given the usual curved form, to 35 provide a rest for the carriage-axle. The long or operating arm of the lever is provided with a lip, I, which engages a series of teeth, J, formed on a curved rack-bar, K, as shown. This rack-bar is carried by the standard C, 40 being secured thereto at its ends, as shown.

Instead of forming the rack-bar integral with the standard, as shown, it could be made separate and bolted or otherwise secured to the standard. I prefer to have it form an integral part of the standard, as thereby the 45 device can be made more compactly and neat-

ly. The lip I is made of sufficient length to engage the teeth J, whichever of the pivot-holes G the pivot of the lever may be inserted through.

5c The operation of the device will be readily understood. The jack is placed in position and the standard turned in its support until the carriage or wagon axle rests upon the short arm of the lever. By pressing the long arm 55 of the lever downward the short arm will be raised, and the carriage or wagon consequently lifted, so as to allow the removal of the wheel and oiling of the axle, as will be understood. The lip I will engage the ratchet-teeth, and 6c the lever will consequently be held in the position given it.

It will be observed that I have provided a jack which can be used with vehicles of any height whatever, as any desired adjustment 65 of the lever can be obtained by means of the series of pivot-holes G and the screw-threaded shank D, working in the support B.

Having thus described my invention, what I claim, and desire to secure by Letters Patent, is—

1. As a new article of manufacture, a lever for wagon-jacks, having a curved portion which forms a rest for the axle of the vehicle, and having its long arm provided with a lip, 75 substantially as and for the purposes specified.

2. The combination, in a wagon-jack, of the hollow internally - screw - threaded support erected upon a suitable base, a standard having a depending screw-threaded shank working in the hollow support, a curved rack-bar secured to the standard, and a lever pivoted to the said standard and provided with a lip which engages the teeth on the curved rack- 85 bar, substantially as described and shown.

In testimony whereof I affix my signature in presence of two witnesses.

CHARLES SPRINGER.
